US0D1082848S

(12) **United States Design Patent** (10) Patent No.: **US D1,082,848 S**
 Saran et al. (45) Date of Patent: ** Jul. 8, 2025

(54) **DISPLAY SCREEN WITH GRAPHICAL USER INTERFACE**

(71) Applicant: **ParkStash Inc.**, San Jose, CA (US)

(72) Inventors: **Sameer Saran**, San Jose, CA (US);
Hooman Bolandi, Los Gatos, CA (US)

(73) Assignee: **ParkStash, Inc.**, San Jose, CA (US)

(**) Term: **15 Years**

(21) Appl. No.: **29/806,519**

(22) Filed: **Sep. 3, 2021**

(51) LOC (15) Cl. **14-04**

(52) U.S. Cl.

USPC **D14/485**

(57) **CLAIM**

The ornamental design for a display screen with graphical user interface, as shown and described.

DESCRIPTION

The patent or application file contains at least one drawing executed in color. Copies of this patent or patent application with color drawing(s) will be provided by the Office upon request and payment of the necessary fee.

The sole FIGURE is a front view of a display screen with graphical user interface.

The broken line illustrates a display screen and forms no part of the claimed design.
